Patented Apr. 19, 1921.

UNITED STATES PATENT OFFICE.

JOHN T. WANN, OF BERKELEY, CALIFORNIA, ASSIGNOR, BY MESNE ASSIGNMENTS, TO
ROBERT C. NEWELL AND WM. C. MURDOCH, JR., BOTH OF SAN FRANCISCO, CALI-
FORNIA.

EVAPORATOR.

1,375,431.

Specification of Letters Patent. Patented Apr. 19, 1921.

Application filed May 4, 1920. Serial No. 378,754.

To all whom it may concern:

Be it known that I, JOHN T. WANN, a citizen of the United States, residing at Berkeley, in the county of Alameda and 5 State of California, have invented a new and useful Improvement in Evaporators, of which the following is a specification.

This invention relates to an apparatus for drying or evaporating fruits, vegetables and 10 other products and especially to improvements in the structure shown in my former patent entitled "Evaporator" issued March 3, 1914, No. 1,089,027.

One of the objects of the present invention 15 is to provide a drier of large capacity especially adapted for handling fruits, vegetables and like food products, and particularly an evaporator adapted to receive the drying trays in stacked formation and so 20 arranged that each will receive a desired volume of dry heated air.

Another object, which forms the special 25 feature of the present invention, is the provision of a series of convex deflecting plates or shields which serve several functions: first, a shield for protecting the lowermost trays against exposure to excessive heat; second, that of directing and deflecting the air toward the inlet flues; third, that of admitting 30 the required amount of heated air to the lower trays; and fourth, that of bypassing a certain amount of the heated air to the exit flues, thereby maintaining the discharging moist air in motion or increasing 35 the flow or velocity to insure complete and rapid discharge of the same.

Further objects will hereinafter appear.

The invention consists of the parts and the construction, combination and arrangement of parts as hereinafter more fully described and claimed, having reference to the accompanying drawings, in which—

Figure 1 is a side elevation of the drier partially in section and partly broken away. 45 Fig. 2 is a plan section on line 2—2, Fig. 1.

Referring to the drawings in detail, A indicates a housing which in this instance is divided into a heating compartment, a 50 drying compartment and an exit compartment, said compartments being respectively indicated at 2, 3 and 4. The lower portion of the housing is in this instance constructed of concrete, while the upper portion is constructed of wood or similar material. 55

The lower or heating compartment is provided with a suitable type of furnace 5, from which extend tortuous or zig zag heat flues or tubes 6. The function of the tubes is to heat an incoming volume of air admitted through inlet passages 7, formed adjacent the floor of the structure. Erected within the drying compartment is a series of vertical racks 8 forming substantially a kiln, the racks being adapted to receive and support in an inclined position a suitable number of drying trays provided for the reception of fruit, vegetables or other products.

The housing, referring to Fig. 2, is sufficiently wide to receive two or more trays on each rack, which may be inserted from either side through doors, such as indicated at 9. The tray receiving racks are arranged in pairs as shown in Fig. 1, and they are 75 spaced apart to form a central discharge flue 10 which communicates with the upper exit chamber 4, and to provide inlet flues 11 on the exterior sides which communicate with the heating chamber 2.

There are five groups of tray supporting racks shown in the present instance, each having a central discharge passage 10 and each having inlet flues arranged on opposite sides as at 11.

In order to insure a proper flow or distribution of air through and between the trays so that all will be subjected to an even temperature, I provide a series of baffle plates 13. These are disposed in the inlet flues or passages and extend crosswise of the housing. The plates are of varying lengths as shown and deflect the upwardly rising currents of heated air inwardly between the trays. To further insure proper distribution of the air a series of convex deflecting plates or shields have been provided. These plates are disposed below each group of tray supporting racks and serve several functions: first that of shielding the lowermost trays against exposure to excessive heat; secondly that of deflecting the main volume of heated air upwardly into the inlet flues; thirdly, that of admitting a certain volume of heated air to the exit flues; and fourthly that of admitting a small amount of heated air to the lowermost trays without passing through the inlet flues. This is accomplished in the following manner: The plates 14 are lined with a suitable 110

heat insulating material, such as asbestos and the like, and this, together with the plates 14, is perforated as at 15 to permit a certain amount of heated air to pass directly through the plates in an upward direction through the lowermost trays, and also a small portion of air to pass upwardly through the exit flues. The perforations insure a sufficient flow of air through the shields to supply the lowermost trays, and also a sufficient flow of air through the exit flues to insure proper velocity and movement of discharging moist air and it at the same time serves as a shield which protects the lowermost trays against excessive heat radiating from the furnace and the pipes 6 in the main heating chamber. Their convex form is also of importance as it deflects the major portion of air into the inlet flues where it is finally distributed or deflected between the trays by means of the plates 13. The air then passes through and between the trays and here absorbs moisture liberated by the material handled. It then escapes into the centrally disposed exit flues and finally enters the exit chamber 4 and a tower 16 communicating therewith, which insures a better draft or circulation of air through the drier as a whole.

From the foregoing description it can be seen that an ideal arrangement has been provided for deflecting and regulating the flow and distribution of the heated air and that this air after its work has been performed is immediately discharged through the exit flues 10; the velocity of discharging air being maintained by admission of hot air as previously described. No tray is therefore exposed to moisture laden air as the air is not re-used, due to the fact that it is permitted to escape immediately after its passage over the trays.

Again it will be seen that a substantial structure of large capacity has been provided and that the trays may be inserted from either side due to the doors provided. A large capacity is in this manner obtained which may be readily handled due to the accessibility of the structure. Practically any type of furnace may be employed as the products of combustion are discharged exterior of the drier through the tubes 6 and a stack 6^a. Contamination or smoking of the fruit or product handled is thus prevented and practically any material may in this manner be handled.

While the tray receiving partitions or racks are here shown as stationary, and certain other features of the invention are more or less specifically illustrated, it is obvious that changes may be resorted to by those skilled in the art without departing from the spirit of my invention as indicated by the appended claims.

Having thus described my invention, what I claim and desire to secure by Letters Patent is—

1. An evaporator comprising a housing, a heating, a drying and an exit chamber formed therein, a plurality of pairs of interspaced tray receiving chambers formed in the drying chamber, inlet flues arranged on one side of each of said chambers and communicating with the heating chamber, an exit flue on the opposite side communicating with the exit chamber, and a heat deflecting means positioned below each pair of tray receiving chambers.

2. An evaporator comprising a housing, a heating, a drying and an exit chamber formed therein, a plurality of pairs of interspaced tray receiving chambers formed in the drying chamber, inlet flues arranged on one side of each of said chambers and communicating with the heating chamber, an exit flue on the opposite side communicating with the exit chamber, and a convex deflecting plate positioned below each pair of tray receiving chambers adapted to direct the main volume of air upwardly into the inlet flues and a portion of the air upwardly between the lowermost trays.

3. In an evaporator of the character described, a drying chamber, a plurality of pairs of tray receiving chambers formed in the drying chamber, an exit flue centrally disposed between each pair of tray receiving chambers, inlet flues arranged on the exterior sides of the tray receiving chambers, and a convex perforated plate disposed below each pair of tray receiving chambers adapted to direct a major volume of heated air upwardly into the inlet flues, and a smaller volume upwardly between the lowermost trays and also upwardly through the exit passages.

4. In an evaporator of the character described, a drying chamber, a plurality of pairs of tray receiving chambers formed in the drying chamber, an exit flue centrally disposed between each pair of tray receiving chambers, inlet flues arranged on the exterior sides of the tray receiving chambers, and means positioned below each pair of tray receiving chambers adapted to direct a major volume of heated air upwardly through the inlet flues and a comparatively smaller volume of heated air upwardly through the lowermost trays, and also upwardly through the exit passages.

In testimony whereof I have hereunto set my hand in the presence of two subscribing witnesses.

JOHN T. WANN.
